UNITED STATES PATENT OFFICE

2,173,874

ADJUSTABLE INK FOUNTAIN OF A ROTARY PRESS

Donald L. Boyd, Huntington, W. Va., assignor to Carb-O-Spot Corporation, Athens, Ohio

Original application June 28, 1938, Serial No. 216,192. Divided and this application November 30, 1938, Serial No. 243,087

3 Claims. (Cl. 101—351)

My invention relates to the type of press described in my copending application, Serial No. 216,192, filed June 28, 1938, of which this application is a division, and further relates to printing presses in which in practice it may be found desirable to lower the ink fountain.

My invention has for its object to provide a simple and inexpensive means whereby this may be done without interfering with the operation of the press.

My means of accomplishing the foregoing object may be more fully comprehended by having reference to the accompanying drawings, which are hereunto annexed and are a part of this specification, in which:

Fig. 1 is a side elevation of my improved press from the gear side, with the oil pump, pipe and pipe connections left out for clarity;

Fig. 2 is a side elevation of my improved press from the feeder side, with the oil pump, pipe and pipe connections left out for clarity;

Fig. 3 is a rear view of the press, with the oil pump, pipe and pipe connections left out for clarity;

Fig. 4 is a fragmentary side elevation showing the drive for the form and distributor rollers, and the means for raising and lowering the ink fountain;

Fig. 5 is a fragmentary side elevation of the ink fountain in lowered position;

Fig. 6 is a plan view of the ink fountain; and

Fig. 7 is a transverse cross section of the ink fountain showing the relative position of ink fountain roller, form roller and plate cylinder.

Similar reference numerals refer to similar parts throughout the entire specification.

For illustrative purposes, I have shown a rotary press equipped with my improvement but it will be obvious to persons skilled in the art, from the hereinafter contained description, that my invention is not restricted to that particular type of press but can be applied to any printing press in which it is desired to lower the ink fountain.

As shown in the drawings, the press consists of two side frames 1 and 2 in which are mounted shafts 3 and 4 adapted to carry an impression cylinder 5 and a plate or printing cylinder 6. The ink fountain 7 is mounted adjacent the plate cylinder 6 which cylinder is contacted by a form cylinder 8. The form roller 8 in turn is contacted by an ink fountain roller 9 which is mounted partially in immersed position in the ink fountain 7.

The ink fountain 7 is mounted upon support bars 10 which are located adjacent each end of

the ink fountain 7. These bars 10 are mounted on shaft 11 and are supported by links 12. The ends 13 and 14 of the links 12 are pivotally secured to the support bars 10. Their other ends 13a and 14a are pivotally secured to one end of a lifting cam 15. This lifting cam 15 is fixed upon a shaft 16. Its opposite end 17 is engaged by a lever 18, one end 19 of which forms a detent 20 which engages the end 17 of the lifting cam 15. The lever 18 is fixed to shaft 21 and is provided for the purpose of locking the lifting cam when the ink fountain 7 is in raised position.

A suitable treadle 22 is formed on one end of the lever 18 or it may be secured to shaft 21 for the purpose of disengaging detent 20 from end 17 when the fountain 7 is lowered. Handle 23 is secured to shaft 16 for imparting movement to lifting cam 15. When it is desired to remove the ink fountain roller 9 or to keep it out of contact with the ink in the ink fountain 7, lever 18 is released from cam 15 and by lowering handle 23 movement is imparted to shaft 16 turning the cam 15 downwardly and carrying with it the links 12 and with them the support bars 10 and in turn the ink fountain 7. Obviously, movement in the opposite direction will restore the parts to their normal operating position.

Upon reference to Fig. 4 of the drawings, it will be noted that a plurality of tubes have been provided to interconnect the form roller 8, the ink fountain roller 9 and the jacket of the ink fountain 7. These tubular connections permit the circulation of fluid through the rollers and ink fountain jacket to maintain the parts at the temperatures necessary to promote efficient operation of the press. The circulation of the fluid may be effected by means of a pump 59 delivering through a tube 60 and a suitable swivel joint to the interior of the ink fountain roller 9, then through suitable connections (not shown) at the opposite end of the ink fountain roller to the form roller 8, then through a suitable swivel joint and a tube 61 to the jacket of the ink fountain 7, and finally back to the pump through a tube 62. In order to permit adjustment between the rollers and the ink fountain, the tubes 60 and 61 have been provided with flexible connections or expansion joints 63 and 64, all of which has been described in my copending application to which reference already has been made.

Having described my invention, what I regard as new and desire to secure by Letters Patent, is:

1. In a rotary press, having a jacketed fountain adapted to contain a supply of ink, a fountain roller normally contacting said ink, a second roll-

- er fed by said fountain roller; a flexible tubular connection between one of said rollers and the jacket of said fountain for the circulation of fluid, and means to drop the ink fountain with respect to said rollers.
5. 2. In a rotary press, having a jacketed ink fountain, an ink fountain roller, a roller intermediate said fountain and the material to be printed; a tubular connection containing an expansion joint between one of said rollers and the jacket of said fountain for the circulation of fluid, and means to lower said fountain with respect to said rollers.
10. 3. In a rotary press, having a jacketed ink fountain, an ink fountain roller, a form roller contacting said ink fountain roller; a flexible fluid connection between one of said rollers and the jacket of said fountain, means to support said ink fountain in elevated position, said means comprising pivoted support bars, a cam, links which connect one end of said cam to said support bars, and actuating means to shift the position of said cam to raise or lower the support bars and in 10 turn the ink fountain.

DONALD L. BOYD.
